US00D963087S

(12) **United States Design Patent** (10) **Patent No.:** **US D963,087 S**
Nicolette et al. (45) **Date of Patent:** **** Sep. 6, 2022**

(54) **GOLF CLUB HEAD**(71) Applicant: **PARSONS XTREME GOLF, LLC**,
Scottsdale, AZ (US)(72) Inventors: **Michael R. Nicolette**, Scottsdale, AZ
(US); **Bradley D. Schweigert**, Cave Creek, AZ (US)(73) Assignee: **PARSONS XTREME GOLF, LLC**,
Scottsdale, AZ (US)(**) Term: **15 Years**(21) Appl. No.: **29/787,969**(22) Filed: **Jun. 9, 2021****Related U.S. Application Data**

(60) Division of application No. 29/698,932, filed on Jul. 22, 2019, now Pat. No. Des. 923,729, which is a continuation-in-part of application No. 29/679,120, filed on Feb. 1, 2019, now abandoned.

(Continued)*Primary Examiner* — Mitchell I. Siegel(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1. The broken lines shown on the drawings form no part of the claimed design.
